SWITCH ACTUATING MECHANISM

Henry W. Grikscheit, Detroit, Mich.

Application November 3, 1948, Serial No. 58,065

5 Claims. (Cl. 200—47)

1

This invention relates to limit switches and particularly to an improved construction for the mechanical actuation thereof.

The general object of the invention is to provide a construction for a limit switch assembly, including an actuating mechanism for the electrical units thereof, which possess such flexibility that the device can be readily designed to meet the operating requirements in practically all instances where limit switches are employed. This flexibility involves the ability to meet changes in operational requirements which include the following principal factors:

Amount of movement of the switch actuating member necessary for operation of the electrical switch elements;

Permissible amount of overtravel of the actuating member following operation of such elements;

The number and type of electrical switch elements required, and in cases where multiple electrical switch elements are employed, the simultaneous or sequential operation thereof.

A satisfactory embodiment of the invention is illustrated in the accompanying drawings and will be described in detail in this specification together with the manner in which variations in the factors of flexibility outlined above can be incorporated by minor modifications from this specific construction. These drawings consist of—

Fig. 1, a plan view of a limit switch assembly with the cover of the case thereof removed;

Fig. 2, a section in elevation taken along the line 2—2 of Fig. 1 and showing the cover in place;

Fig. 3, an elevation of a portion of the limit switch showing the actuating member thereof;

Fig. 4, a section taken along the line 4—4 of Fig. 1;

Fig. 5, a detail taken along the line 5—5 of Fig. 2 and showing the attachment between the actuating member and the limit switch assembly;

Fig. 6, a detail taken along the line 6—6 of Fig. 1 and showing the connection between an electrical switch element and the assembly.

All limit switch assemblies contain, as common elements, an electrical switching element and an actuating member for the switch assembly together with a mechanism of some kind to produce operation of the electrical element upon movement of the actuating member. The electrical element may be considered as a sub-assembly and is chosen according to the particular electrical function to be performed by the switch.

These features are also found in the present construction which includes two electrical switch elements 11, mounted within a suitable case or housing 12, and an actuating member 13, the

2

operation of the device being such that the electrical switch elements 11 function in response to rotation of the actuating member 13. Limit switches are used for a wide variety of purposes each of which may require slight differences in the operation of the switch in order that it may perform its intended function. The most frequent variations between switches consist in changes in operation caused by changing one or more of the variable factors previously enumerated. For example, in a specific installation for a limit switch, it may be necessary that the electrical switch element be operated upon 10° of rotation of the actuating member and that such actuating member then be able to move an additional number of degrees of overtravel. For a second installation, it may be desirable to provide a switch which functions in the same manner but which includes a different number of electrical switch elements. In a third case, a different amount of actuating travel and/or overtravel of the actuating member may be required; while, in another instance, the function of the limit switch may specify a construction in which one electrical element operates after a certain number of degrees of movement of the actuating member while a second element operates after some additional number of degrees of movement.

Other possible variations include the return movement of the actuating member which, in one case, may be automatic and, in another, manual. As previously mentioned, the principal object of the present invention is to provide a limit switch actuating mechanism which, through slight variations, can be modified to effect any of the foregoing changes in the functioning of a switch or any combination of such changes.

Other objects include the provision of an actuating mechanism which is adaptable to standard commercial types of electrical switch elements; the provision of a limit switch wherein the actuating member can be accurately adjusted to the desired initial position; and the provision of an actuating mechanism which will be particularly resistant to shock or sudden impacts against the actuating member. Other more specific objects and advantages of the invention will be developed in connection with the more detailed description thereof which follows.

The construction illustrated in the drawings employs two electrical switch elements 11, each having two normally open and two normally closed contacts. Such switch elements are standard commercial units in which the contacts are operated by movement of a push button 14 which is normally urged downwardly (referring to the sectional views of Figs. 2 and 4), by a spring within the unit. These electrical units are mounted in

side by side relation within the case and are separated from the bottom thereof by suitable spacing blocks 15 and 16 and held in position by screws 17. The operating arm 13 is attached to a hub plate 18 which, in turn, is keyed to a collar 19 rotatable with a shaft 20 which projects outwardly from the bottom of the case 12. That portion of the case surrounding the shaft is formed as a bearing housing 21 and a pair of ball bearings 22 extend between this housing and the shaft to support the latter. The inner portion of the shaft 20 is formed as a post 23 of increased diameter to provide a shoulder 24 which abuts against the inner race of the inner bearing 22. A circular cam plate 25 is firmly attached to this post along an angular supporting surface 26 formed on the inner end thereof so as to lie at an angle to the longitudinal axis of the shaft.

Extending between the pair of electrical switches 11 is a rocker arm or main actuating member 27, one end of which is mounted between a yoke formed by a pair of vertical members 28 which are fabricated as part of the spacer block 15. A pivot pin 29 serves as a connection between the rocker arm and the yoke members 28, and from this pivot pin the rocker arm extends between a U-shaped guide and stop 30. The free end of the rocker arm is provided with a stub shaft 31 upon which a roller bearing follower 32 is mounted so as to contact the underside of the cam plate 25. Two notches 33 are cut in the underside of the rocker arm to define a projecting lug 34, which acts as a retaining member for one end of a compression spring 35, the other end of this spring being held within a circular recess 36 formed as part of the spacer block 16, so that the spring therefor urges the rocker arm 27 and its follower 32 upwardly into engagement with the underside of the cam plate 25. Upward movement of the rocker arm, however, is limited by the stop 30. In the construction illustrated, the cam plate 25 is provided with a rectangular notch 39 which is engaged by the follower 32 of the rocker arm to define the normal or neutral position of the actuating member.

Actuation of the push buttons 14 of the electrical switches is accomplished by a spring plate or switch actuating element 37, one end of which is held in position by being gripped between the spacer block 15 and the bottom of the case. A stirrup member 38 is attached to the free end of this plate and straddles the rocker arm 27 to provide a one-way connection between the plate and rocker arm. During upward or return movement of the rocker arm toward the neutral position shown in Fig. 2, its upper surface engages the cross-bar 42 of the stirrup member 38, causing upward movement of the plate 37 against the push buttons of the switch elements, depressing them to a new contact position and at the same time producing tension in the spring plate 37. Downward or actuating movement of the rocker arm releases this tension and is accordingly accompanied by downward movement of the spring plate. Since the switch element push buttons are normally urged downwardly by their own spring means (not shown), movement of the spring plate downwardly is followed by downward movement of the push buttons until the switch contact elements reach a new position.

In the initial installation of a limit switch assembly, it is frequently necessary to adjust the radial position of the operating arm 13 rela-

tive to the shaft 20 for proper operation of the unit. A vernier type construction has been incorporated in the hub plate 18 and collar 19 for this purpose, as is best shown in Figs. 2, 3 and 5, and consists of a series of equally spaced holes 43 drilled in the outer face of the collar 19. A second series of holes 44 are formed in the hub plate 18 at a radial distance from the center of the shaft 20 equal to that of the holes 43, there being a greater number by one of the holes 44 than of the holes 43. For example, in the present construction, as illustrated in Fig. 5, nine holes 44 are provided in the hub plate 18 while eight holes 43 are spaced around the center of the collar 19. The hub plate is keyed to the collar by a washer 45 having a lug 46 adapted to be inserted within a hole 44 of the hub plate and to project into an aligned hole 43 of the collar. A nut 47, engaging a threaded portion 48 of the shaft 20, holds the actuating arm on the shaft.

Studs 49, provided with nuts 50, project from one end of the case for mounting the limit switch assembly, as to the member 51, and a boss 52, equipped with internal pipe threads, is located at the other end of the case for the connection of an electrical conduit 53. The case is enclosed by a cover 54 and the electrical connections to the switch elements are segregated and insulated from the adjacent moving parts of the actuating mechanism by a U-shaped section of insulating material 55.

For operation of the switch, rotary movement of the operating arm 13 is initiated in some extraneous manner. This rotation is accompanied by a rotation of the shaft 20 and cam plate 25 and causes the follower 32 and the free end of the rocker arm to be depressed against the force of the spring 35. The spring plate 37 has a normal direction of movement away from the push buttons 14 and is held in contact with the push buttons only by the engagement between the stirrup 38 and upper surface of the rocker arm 27. Downward movement of the rocker arm therefore is accompanied by a downward movement of the spring plate 37 allowing the push buttons 14 to move downwardly and place the contacts within the switch elements in a new position. In the construction shown, the force of the spring 35 has been correlated with the angle of the cam plate 25 so that the upward pressure of the roller 32 against the underside of the cam plate will be sufficient to cause rotation of the latter and return the actuating member to normal position. This spring 35, of course, must also be designed to have sufficient strength to distort the spring plate 37 during this returning movement.

It is to be noted that the combination of main actuating member 27, switch actuating member 37 and stirrup 38 used to produce movement of the push buttons 14 effects a one-way connection between the actuating mechanism and the electrical switches with the result that movement of the main actuating member in an actuating direction is not limited to the small amount of movement required by the push buttons. The notch 39 in the cam plate has been made rather wide relative to the diameter of the follower 32, so that a large movement of the main actuating member accompanies a relatively small amount of initial rotation of the operating arm 13. The precise construction illustrated may, therefore, be said to have the following operational features.

The electrical switches are very sensitive in

responding to movement of the operating arm 13 and, in this respect, approximately 5° of rotation thereof causes sufficient downward movement of the rocker arm 27 to extend the push buttons and cause a change of electrical contacts within the switches. A large amount of overtravel of the operating arm is permissible following this initial actuation, such overtravel in this particular construction being approximately 120°. Operation of the two electrical switches is simultaneous and in this connection since no two switch units will be actuated by precisely the same amount of movement of their push buttons, a washer 40 of some suitable compressible material (see Fig. 6) is interposed between the lower surface 41 of the switch unit and the upper surface of the supporting spacer block so that the vertical difference between the bottom of the case 12 and switch unit can be varied within the small limits necessary for this adjustment by turning the screws 17.

Modifications to the specific structure shown to vary the operating characteristics of the switch assembly should be obvious to those skilled in the art, but will be briefly outlined. The amount of rotation of the operating arm required for operation of the switch elements can be changed by design changes in the diameter of the follower 32 and/or the width of the notch 39, or, if a large amount of rotation is desired, the notch can be eliminated and the cam plate made with a slope that will cause the proper form of operation. Overtravel of the operating arm following switch operation is also a function of the slope of the cam plate.

Sequential operation of switch elements can be attained by positioning at different levels or by the use of multiple followers and associated parts, and other changes would include the use of multiple notches on the cam plate to give a number of actuations during a complete rotation of the actuating member.

The possibility of such minor changes is mentioned principally to illustrate the flexibility or adaptability of the invention, which is thought to constitute one of its more important features.

I claim:

1. A switch actuating mechanism for use in combination with a multi-position, push button operated switch element, comprising a switch actuating member mounted adjacent said switch element and adapted to contact the push button thereof, said member being spring urged in a direction away from contact with said push button, a main actuating member, spring means associated therewith and urging said main actuating member in the opposite direction from the spring induced movement of said switch actuating member, means to establish a one-way connection between said members whereby said switch actuating member will be moved into contact with said push button upon spring-urged movement of said main actuating member and means to control movement of said main actuating member.

2. A switch actuating mechanism comprising a case, a shaft journaled therein, an operating member attached to said shaft, a cam plate carried by said shaft at an angle to the longitudinal axis thereof, a main actuating member pivotally mounted within said case and having its free end spaced from said shaft, spring means normally urging said free end of said main actuating member into contact with said cam plate, a switch actuating element positioned beneath

said main actuating member and spring urged in a direction opposite to the spring-urged movement of said main actuating member, means to establish a one-way connection between said main actuating member and said switch actuating element, said spring means being capable of overpowering the spring-urged movement of said switch actuating element, and a stop member positioned to limit the spring-urged movement of said main actuating member.

3. The invention set forth in claim 1 wherein the means to control movement of said main actuating member comprises a shaft, an operating arm mounted thereon to rotate therewith, and a cam fixed to said shaft, said cam contacting said main actuating member and having a control surface adapted to cause movement of said main actuating member against said spring means upon rotation of said operating arm.

4. A switch actuating mechanism comprising a case, a shaft journaled therein, an operating member attached to said shaft, a cam plate carried by said shaft, a main actuating member pivotally mounted within said case and spring urged into contact with said cam plate, a switch actuating element spring urged in a direction opposite to the spring urged movement of said actuating member, a stirrup member carried by said switch actuating element and straddling said main actuating member, said stirrup being engaged by said main actuating member on spring urged movement thereof.

5. A switch actuating mechanism for use with a switch element of the type wherein the switch contacts thereof are normally urged to one position and movable to a second position, comprising a movably mounted switch actuating member normally urged in a direction of movement corresponding to the normally urged direction of movement of said switch contacts, a main actuating member spaced from said switch actuating member and mounted for actuating and return movement, said actuating movement corresponding in direction to the normally urged direction of movement of said switch actuating member, one-way motion transmitting means interposed between said main actuating and switch actuating members comprising a stirrup connected to said switch actuating member and straddling said main actuating member, said motion transmitting means operating to release said switch actuating member for the normally urged movement thereof during movement of said main actuating member in an actuating direction and to positively impart movement to said switch actuating member during return movement of said main actuating member, and means to produce actuating and return movement of said main actuating member comprising a spring normally urging said main actuating member in a return direction of movement, and a control cam contacting said main actuating member and adapted to produce actuating movement thereof.
